Attorney.

UNITED STATES PATENT OFFICE.

EDWARD C. DEARDEN, OF MERION TOWNSHIP, MONTGOMERY COUNTY, PENNSYLVANIA, ASSIGNOR TO THE GEO. W. BLABON COMPANY, OF PHILADELPHIA, PENNSYLVANIA, A CORPORATION OF PENNSYLVANIA.

INLAID-LINOLEUM MACHINE.

1,186,082.

Specification of Letters Patent

Patented June 6, 1916.

Application filed November 11, 1915. Serial No. 60,809.

To all whom it may concern:

Be it known that I, EDWARD C. DEARDEN, a citizen of the United States, residing in the township of Merion, county of Montgomery, and State of Pennsylvania, have invented certain Improvements in Inlaid-Linoleum Machines, of which the following is a specification.

My invention relates to improved machinery for making inlaid products, particularly linoleum floor cloth, and its primary object is to provide a simple and efficient machine of flexible character for making straight line products by an automatic operation comprising punching different shapes from two or more sheets of composition and setting them in the desired relation upon an intermittently moving backing fabric.

My improved machine, in its preferred form, is characterized by a plurality of tables forming a bed over which a backing fabric is moved intermittently, mechanism for carrying a fabric over the bed, a frame comprising a superstructure connected with the respective tables by vertically adjustable guide posts, templets fixed to the posts and held thereby above the tables at distances proportional to the thicknesses of tesserae on the backing fabric passing over the bed, dies or punches attached to plates which are connected with said posts so as to reciprocate thereon with the punches in alinement with the perforations of the templet through which they are adapted to pass, perforated compression plates connected with the head so as to permit the plungers to move therein, the dies being held in alinement by the compression plates, operating mechanism comprising a sectional shaft having cranks connected by pitmen with the die holding plates to effect the reciprocation thereof, and means for cooling the plates and removing scraps.

In the accompanying drawings, Figure 1 is a side elevation of a machine embodying my invention; Fig. 2 is a sectional view taken on the line 2-2 of Fig. 1; Fig. 3 is a sectional view taken on the line 3-3 of Fig. 1; and Fig. 4 is a sectional view taken on the line 4-4 of Fig. 3.

The mechanism, in the form thereof illustrated in the drawings, comprises the aligned tables 1 forming sections of a bed, the frame

2 having the longitudinal side beams 3 connected by the transverse beams 4 disposed above the bed, the vertical hollow guide posts 5 fixed to the tables and side beams, and the templets 6 fixed to the posts a sufficient distance above the bed to pass the fabric, the posts being adjustable by the nuts 5' to vary the distances between the bed and templets to accommodate sheets of various thicknesses.

Reciprocatory plates or heads 7 are guided by the posts and are provided with dies or punches 7', which fit the perforations 6' of the templets and are movable therethrough so as to punch straight line shapes from sheets of material supported by the templets.

Compression plates 8 are connected with the respective heads by bolts 9 and are provided with the perforations 8' which fit the dies, the dies being movable through the plates by the movements of the bolts in the heads and being held in alinement by their engagements in the apertures in such compression plates.

A shaft, comprising the sections 10 having the respective cranks 10' detachably connected by the coupling members 10'', is journaled in the bearings 4' of the frame superstructure and pitmen 11 connect the respective cranks with pins 12 fixed to the heads, whereby the latter are reciprocated.

A spiral gear or worm wheel 13 is fixed on the crank shaft, to effect its revolution, and a worm wheel 14, journaled in the frame, drives the gear, the worm being driven by a pulley 15.

Wheels 16 are journaled at the ends of the machine and carry the spiked belts 17 for translating the fabric 18 over the bed and beneath the templets from a roll of such fabric carried by the roller 19 to a roll of the inlaid product carried by the roller 20, the rollers being journaled at the opposite ends of the machine beyond the carrier belts.

The belts 17 and fabric 18 thereon are moved intermittently in alternation with the operation of the dies by a gear wheel 16^a fixed on the journaled shaft 16^b which carries wheels 16. The gear 16^a meshes with 16^c, having a radially slotted star wheel 16^d fixed thereto and revolved intermittently in a

well known manner by the revoluble device 16^e carrying the pin 16^f adapted to enter the slots. The device 16^e is revolved by a gear 16^g fixed thereto and engaged by a journaled 5 pinion 16^h driven by a pulley 16ⁱ.

A cooling system for the templets comprises a pipe 21 having branches 21' which are connected with the bottoms of hollow posts 5 on one side of the machine, the 10 branches being provided with the valves 21'' for controlling the flow of cooling fluid therethrough. The hollow posts communicate with conduits 22 extending around the respective templets and these conduits discharge through hollow posts 5 connected with the discharge pipe 23 through the branches 23', the latter containing the valves 23''.

Nozzles 24 are connected with suction 20 pipes 24' and are loosely hung above the frame so that particles broken from the material as the tesserae are cut can be sucked up.

In the machine, as here illustrated, an inlaid product can be produced comprising a straight line pattern having four figures, and by uncoupling one or more of the connections 10'' from the rear end of the machine a pattern having a reduced number 30 of figures may be formed.

It will be understood that the operation is effected by revolving the shaft 10 and actuating the belt 17, by the mechanisms described, so as to carry the fabric 18 over 35 the tables 1 forming the bed in a step by step movement for the purpose of positioning the sections that are to receive while stationary the several shapes forming the design. Sheets of composition having different colors are placed upon the respective 40 templets 6, held in the desired positions by the compression plates, and the desired shapes forced from such sheets through the different apertures 6' by the descent of the 45 dies which place the tesserae in proper position upon a backing 18. The rise of the heads or plates 7 withdraws the punches 7' from the templets 6 and the sheets of composition thereon, the plates 8 resting upon

and holding such sheets until the punches 50 have been withdrawn therefrom as a result of the limited upward movement permitted the heads with relation to the plates by the bolts 9.

Having described my invention, I claim: 55

1. In a machine for making straight line inlaid products, a plurality of tables, means for carrying a backing fabric over said tables, apertured templets above the respective tables, reciprocatory heads having 60 punches adapted for passing through apertures of the respective templets, plates adapted for holding material on said templets, said plates having apertures registering with the respective punches, bolts loosely 65 connecting said heads and plates, and means comprising a sectional crank shaft for reciprocating selected heads aforesaid.

2. In a machine for making straight line inlaid products, the combination with a plurality of aligned tables, of means for carrying a fabric over said tables, a shaft having separable crank sections journaled above said tables, guiding means adjacent to said tables, templets supported by said guiding means, 70 heads guided by said guiding means and having plungers for forcing material through said templets, and means for connecting said crank sections with said heads. 75

3. In a machine for making straight line 80 inlaid products, the combination with a plurality of aligned tables, of a plurality of shaft sections journaled above said tables, each of said sections having a crank, detachable couplings for connecting said sections, pitmen connected with said cranks, plungers operable by said pitmen, and templets 85 through which material is forced by said plungers to fabric on said tables.

4. In a machine for making straight line 90 products, the combination of a table, a templet held above said table, means for supplying cooling fluid to said templet, and punches adapted for reciprocating through said templet. 95

In testimony whereof I have hereunto set my name this 3rd day of November, 1915.

EDWARD C. DEARDEN.
